NOZZLE FOR A HYDROMASSAGE UNIT

Robert H. Hurst, Barrington, R.I., assignor to Clevepak
Corporation, New York, N.Y.

Filed Oct. 13, 1972, Ser. No. 297,445

Term of patent 14 years

Int. Cl. D24—04

U.S. Cl. D83—1 C

FIG. 1

FIG. 2

FIG. 3

FIG. 4

FIG. 5

FIG. 1 is a side elevation view of a nozzle for a hydromassage unit, showing my new design.

FIG. 2 is a top plan view of the design of FIG. 1.

FIG. 3 is a bottom plan view of the design of FIGS. 1 and 2.

FIG. 4 is a front elevation.

FIG. 5 is a rear elevation.

I claim:

The ornamental design for a nozzle for a hydromassage unit, as shown.
